CLAIM

The ornamental design for a shoe midsole periphery, as shown and described.

DESCRIPTION

FIG. 1 is a perspective view of a shoe midsole periphery in accordance with my new design.

FIG. 2 is a left side elevation view thereof;

FIG. 3 is a right side elevation view thereof;

FIG. 4 is a top plan view thereof;

FIG. 5 is a bottom plan view thereof;

FIG. 6 is a front elevation view thereof; and,

FIG. 7 is a rear elevation view thereof.

The broken lines shown in the drawings represent portions of the shoe upper, midsole periphery, and outsole bottom that form no part of the claimed design. The dot-dash broken lines show the boundaries of the claimed design. The dot-dash broken lines also form no part of the claimed design.
